SLING SHOT

Charles E. Jones, Colorado Springs, Colo., assignor to
Colorado Springs Machine Corporation, Colorado
Springs, Colo.

Filed Jan. 14, 1972, Ser. No. 218,053

Term of patent 14 years

Int. Cl. D22—01

U.S. Cl. D22—4

FIG. 1

FIG. 2

FIG. 3

FIG. 4

FIG. 1 is a perspective view of a sling shot embodying my new design;

FIG. 2 is a front elevational view thereof, the elastic band and sling being omitted for convenience of illustration;

FIG. 3 is a side elevational view thereof; and

FIG. 4 is a top plan view thereof.

I claim:

The ornamental design for a sling shot, substantially as shown and described.
